UNITED STATES PATENT OFFICE.

WILLIAM R. FOWLER, OF BALTIMORE, MARYLAND, ASSIGNOR TO MATHAI,
INGRAM & CO., OF SAME PLACE.

FLY-FAN.

SPECIFICATION forming part of Letters Patent No. 358,807, dated March 1, 1887.

Application filed October 28, 1886. Serial No. 217,424. (No model.)

To all whom it may concern:

Be it known that I, WILLIAM R. FOWLER, a citizen of the United States, residing at Baltimore, in the State of Maryland, have invented certain new and useful Improvements in Fly-Fans, of which the following is a specification.

My invention relates to certain improvements in automatic fans for driving flies.

10 The several features comprising the invention are illustrated in the accompanying drawings, in which—

Figure 1 is a side view of the fan-staff and fans folded up against the staff. Fig. 2 is a 15 side view of the operating parts complete, on a larger scale, and show the combined coupling and stop device in position to prevent the rotation of the fans. Fig. 3 is a side and partly 20 sectional view of the operating parts, omitting the spring which surrounds the fan-staff, and showing the combined coupling and stop device in position to cause the fans to rotate. This figure also includes a cross-section. Figs. 25 4, 5, and 6 are views of the fan-carrier. Fig. 7 is a view of the lower end of the detachable 30 fan-staff. Fig. 8 is a perspective view of the combined coupling and stop device.

The parts here shown are applicable to fly-fan motors of any construction which are supported upon bases to be set upon the table.

The letter A designates the fans, each of 35 which is attached to an arm, a. The stand-tube B is designed to be attached to a base or casing of any well-known construction, and the driving-shaft D projects upward through 40 this tube. It will be understood that rotary motion is to be imparted to this driving-shaft by a motor, which forms no part of the present invention. Any well-known or suitable motor may therefore be used.

The interior of the tube B has a contraction or annular shoulder, b, which serves as a bearing for the driving-shaft D and reduces the friction to a minimum. The top of the tube has 45 a flange, c, provided with one or more catch-lugs, d, for a purpose hereinafter explained.

The upper end of the driving-shaft D has a coupling-tube, E, attached to it by a pin, f.

The lower end of the coupling-tube occupies 50 the top end of the tube B, but does not touch

it, and therefore occasions no friction. The position of the coupling-tube E, projecting as it does upward from the tube B, affords strength and stiffness to the driving shaft and fan-staff at a point where these qualities are most needed. 55 This coupling-tube has at one side a cross-slot, g, and a combined coupling and stop device, F, is pivoted to it at h below the said cross-slot. The device F has the shape in general of a bell-crank lever, the extremity of the upper 60 arm of which has a flange, g', provided at one side with a lug, i. The flange g' enters the cross-slot in the coupling-tube, as shown in Fig. 3, while the lug i, by coming in contact with the side of the tube, prevents the upper arm from 65 moving past the tube. When the flange g' of the upper arm is in the cross-slot g, it effects a coupling with the fan-staff D', which is a round rod having its lower end inserted in the coupling-tube E. The coupling is effected 70 by the flange g' engaging with an annular notch, g'', on said fan-staff. The said flange presses hard on the staff. In this position of the device F the driving-shaft and fans may rotate. The lower arm, d', besides serving as 75 a handle, may, when tilted down, as shown in Figs. 1 and 2, serve as a stop by coming in contact with one of the aforesaid catch-lugs d on the tube B. When the lower arm, d', is engaged with the catch-lug d, the driving-shaft, 80 and of course the fans, cannot rotate. Instead of the catch-lugs d, the flange c may have catch-notches for the arm d'.

From the foregoing it will be seen that the fan-staff and fans may be entirely detached by 85 turning the device F so that its upper arm will be released from the notch g'' on the staff, and then raising the fan-staff out of the tube E.

The two arms a of the fans are pivoted to a carrier, G, which is adjustable on the fan-staff 90 by special means. The carrier is a rectangular ring or frame provided on each of its vertical sides with a pivot-pin, k, and a stop-lug, l. These parts are arranged, as plainly shown in the drawings, so that a fan-arm, a, pivoted to 95 the pivot-pin k at one side, may, when turned to a horizontal position, as in Fig. 3, come against the stop-lug l at the other side, and thereby be sustained in said position. The upper and lower horizontal sides m of the 100

carrier have a round hole, n , through which the round fan-staff D' passes freely. Thus the carrier G may turn on the fan-staff and be raised or lowered. When lowered as far as it is designed to go, its down movement will be arrested by a pin, o, projecting from the fan-staff. The lower horizontal side m of the carrier-frame has a swell, q, on two opposite edges, as seen in Figs. 4, 5, and 6. When the fan-arms a are turned up vertically, as in Figs. 1 and 2, a swell q acts on the extremity a' of each arm, and serves to maintain the arm in its vertical position. When it is desired to turn the fan-arms to a horizontal position for operation, it is necessary only to pull each arm down. In so doing the arm will tilt side-
 10 wise slightly on its pivot-pin k, and the arm extremity a' will spring sufficient to pass the swell q. I have provided in combination with this carrier a spiral spring, p, to sustain the carrier at any point on the fan-staff to which it may be adjusted. The spiral spring p (see Fig. 2) surrounds the shaft closely within the carrier-frame, and its upper and lower ends bear against said frame. One end, p', of the spiral spring projects against the carrier-frame, and thereby controls its turning movement. The normal tension of the spiral spring on the staff is just sufficient to sustain the carrier.
 15 20 25 30 35

If while the fans are turning an object sufficient to stop the fans should come within the

path of their rotation, the construction of the annular notch g² on the fan-staff and the coupling-arm of the device F will allow the fans and fan-staff to be stopped without suddenly arresting the movement of the driving-shaft D. 40

Having described my invention, I claim and desire to secure by Letters Patent of the United States—

1. A fly-fan having a stand-tube, B, provided with an internal contraction or annular shoulder, b, a driving-shaft, D, within said stand-tube, a fan-staff, D', and a coupling-tube, E, 50 attached to the driving-shaft above said annular shoulder b, and with its lower end occupying but not touching the top end of the stand-tube, as shown and described.

2. In a fly-fan, the combination of a stand-tube having one or more catches, d, a drive-shaft tube, E, provided with a cross-slot, g, a fan staff inserted in said drive-shaft tube, and a bell-crank lever, F, pivoted to the drive-shaft tube at a point between the catches and cross-slot, and serving when in one position to couple with the fan-staff and when in the other position to engage with the said catch, as shown and described. 55 6c

3. In a fly-fan, the combination of the fan-staff D', a fan-carrier frame, G, to both turn and slide on the fan-staff, and a spiral spring, p, closely surrounding the fan-staff within the carrier-frame and having one end against said frame, for the purpose set forth. 70

In testimony whereof I affix my signature in the presence of two witnesses.

WILLIAM R. FOWLER.
